2 Sheets-Sheet 2

UNITED STATES PATENT OFFICE

WILLIAM T. BOYD, OF GLENDALE, KENTUCKY

TRAIN-ORDER DEVICE

Application filed January 14, 1929. Serial No. 332,404.

This invention relates to a train order holder, the general object of the invention being to provide a post or upright arranged adjacent a track and having a holder member for receiving the usual bamboo hoop so supported thereon that said member, with the hoop therein, is firmly held against movement by the wind caused by passing trains or a heavy wind itself, but will have free 10 rotary movement about a vertical axis when the hoop is caught by a trainman so that the hoop will pass from the holder without interference on the part of the holder, thus eliminating danger to the trainman catching 15 the hoop.

Another object of the invention is to provide means for removably holding a lantern on the upright so that the parts will be illuminated at night.

20 This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several 30 views, and in which:—

Figure 1 is an elevation of the device.

Figure 2 is an enlarged sectional view showing the supporting means for the holder.

Figure 3 is a section on line 3—3 of Figure 1.

Figure 4 is a section on line 4—4 of Figure 2.

Figure 5 is a sectional view through the upright.

40 Figure 6 is a sectional view through the lantern carrying part of the upright.

Figure 7 is a fragmentary view of one section of the upright, showing the pin therein for engaging the slots in another section.

45 Figure 8 is a top plan view, with parts in section, showing the lantern supporting means.

Figure 9 is a fragmentary view of a section of the upright having the slots therein 50 for receiving the pin in another section.

In these views, the numeral 1 indicates a tubular member embedded in the platform or in a part of the track bed adjacent a track, the upper end of this tubular member having the oppositely arranged slots 2 therein. The 55 numeral 3 indicates a section of an upright which has its lower end fitting in the member 1, with a pin 4 passing through the lower part of the section 3 and engaging the slots 2 for holding the section 3 in the part 1 and preventing rotary movement of the section 3. A top section 5 of the upright is reinforced at its lower part, as shown at 6, and the lower end of this section 5 fits in the upper end of the section 3 and is removably fastened therein by the pin and slot arrangement shown generally at 7, which is similar to that which connects the lower end of the section 3 with the part 1. A pair of sleeves 8 is threaded on the section 5 in spaced relation 70 and a tubular arm 9 passes through each sleeve, the lower arm also passing through the section 5. Each arm is adjustably held in position by a set screw 10 so that the arm can be adjusted longitudinally in the section. A vertical enlargement 11 is connected with the outer end of each arm, or the end toward the track, and a bushing 12 passes vertically through each enlargement. A vertically arranged shaft 13 has its lower part rotatably 75 arranged in each bushing and a tubular member 14 has its inner end fastened to the upper end of the shaft 13, with said member 14 diagonally arranged, as shown.

The member 14 is provided with a depending flanged part 15 which surrounds the shaft 13 and has its flanged portion resting on the upper end of the bushing 12. A block 16 is placed in the member 14 and a pair of prongs 17 each has one end threaded into the member 14 and the block, as clearly shown in Figure 2. These prongs extend forwardly and outwardly relative to the outer part of the member 14. The outer end of the member 14 has its top part cut away to form a forwardly extending tongue 18 which is of curved shape in cross section. As will be understood, one end of a bamboo hoop A, the handle end of which has been cut off, is placed in the forward part of the member 14, as 100

shown in Figure 1, with its other end part 5 engaging the prongs 17 so that the hoop is held against turning movement in the holder member 14. A spring detent 19 is arranged in the tubular arm 9 and engages a recess 20 in the shaft 13. The spring 21 of this detent can be adjusted by the set screw 22 which passes through that end of the arm which is farthest from the track.

10 From the foregoing it will be seen that the detent holds the shaft 13 and the holder member 14 against turning movement and with the holder member in a position to hold the hoop A where a trainman can readily pass his 15 arm through the same. The spring detent will prevent the wind from a passing train from turning the holder member and its shaft, but when a trainman catches the hoop, the detent will yield and permit the shaft 13 20 to turn so that the holder member 14 can turn with the movement of the hoop caused by the trainman catching the same and thus the end of the hoop will readily pass from the holder member. Of course, when the station master 25 or other person wishes to place an order on the device, he will reset the parts with the detent engaging the recess in the shaft 13, so that the parts will appear as shown in Figures 1 and 2.

30 While the drawings show two hoop holding devices on the standard, it will, of course, be understood that one or more than two can be used.

35 A tubular arm 23 is rotatably supported on the upright by the coupling 24 and this arm carries a jaw member 25. A rod 26 is slidably arranged in the arm and carries a jaw part 27. A spring 28 within the arm engages a pin 29 carried by the rod and acts 40 to hold the rod in its inner position. The pin 29 slides in slots 30 formed in the arm. Thus the arm and the rod form a spring clamp for holding a lantern B on the upright for illuminating the parts at night. The inner end 45 of the rod is adapted to pass through any one of a number of holes 31 formed in the upright, so that the lantern carrying means can be placed at right angles to the track or parallel thereto either in front or in rear of the 50 upright.

It is thought from the foregoing description that the advantages and novel features of the invention will be readily apparent.

It is to be understood that changes may be 55 made in the construction and in the combination and arrangement of the several parts, provided that such changes fall within the scope of the appended claims.

What I claim is:—

60 1. A train order holder comprising a standard, an arm extending at rightangles therefrom, a hoop holding member having a part rotatably arranged in the arm, means for yieldingly holding said part against movement, a tubular hoop holder, a shaft depend-

ing therefrom and rotatably arranged in the arm and spring means within the arm and engaging the shaft for yieldingly holding the shaft against rotary movement.

2. A train order holder comprising a standard, an arm extending at rightangles therefrom, a hoop holding member having a part rotatably arranged in the arm, means for yieldingly holding said part against movement, a tubular hoop holder, a shaft depending therefrom and rotatably arranged in the arm, spring means within the arm and engaging the shaft for yieldingly holding the shaft against rotary movement and prongs carried by the tubular member. 70

3. A train order holder comprising a standard, a tubular arm attached thereto and extending at rightangles therefrom, a vertically arranged shaft having its lower end rotatably arranged in the arm, a tubular hoop holder connected with the upper end of the shaft and extending outwardly and upwardly therefrom and a spring detent in the arm and engaging a part of the shaft for yieldingly holding the shaft against rotary movement. 75

4. A train order holder comprising a standard, a tubular arm attached thereto and extending at rightangles therefrom, a vertically arranged shaft having its lower end rotatably arranged in the arm, a tubular hoop holder connected with the upper end of the shaft and extending outwardly and upwardly therefrom, a spring detent in the arm and engaging a part of the shaft for yieldingly holding the shaft against rotary movement, means for adjusting the tension of the spring and prongs carried by the tubular holder. 80

5. A train order holder comprising a standard, a tubular arm attached thereto and extending at rightangles therefrom, a vertically arranged shaft having its lower end rotatably arranged in the arm, a tubular hoop holder connected with the upper end of the shaft and extending outwardly and upwardly therefrom, a spring detent in the arm and engaging a part of the shaft for yieldingly holding the shaft against rotary movement, means for adjusting the tension of the spring, prongs carried by the tubular holder, a second arm on the standard and lantern clamping means carried by said second arm. 85

6. A train order holder comprising a standard, a tubular arm attached thereto and extending at rightangles therefrom, a vertically arranged shaft having its lower end rotatably arranged in the arm, a tubular hoop holder connected with the upper end of the shaft and extending outwardly and upwardly therefrom, a spring detent in the arm and engaging a part of the shaft for yieldingly holding the shaft against rotary movement, means for adjusting the tension of the spring, prongs carried by the tubular holder, a second arm on the standard, lantern clamping means carried by said second arm and means for 90

adjustably connecting the second arm with the standard.

7. A train order holder comprising a standard, a tubular arm attached thereto and extending at right angles therefrom, a vertically arranged shaft having its lower end rotatably arranged in the arm, a tubular hoop holder connected with the upper end of the shaft and externally outwardly and upwardly therefrom, a spring detent in the arm and engaging a part of the shaft for yieldingly holding the shaft against rotary movement, means for adjusting the tension of the spring, prongs carried by the tubular holder, a second arm on the standard, lanterns clamping means carried by the second arm, means for adjustably connecting the second arm with the standard, said standard being formed in sections which are removably connected together.

In testimony whereof I affix my signature.
WILLIAM T. BOYD.
